HART GRAIN WEIGHER CO., OF PEORIA, ILLINOIS, A CORPORATION OF ILLINOIS.

ADJUSTABLE CONVEYER SUPPORT FOR CONVEYERS.

Application filed June 7, 1922. Serial No. 566,579.

To all whom it may concern:

Be it known that we, ARTHUR J. HARTLEY and WILLIAM HALE, citizens of the United States of America, residing at Peoria, in the county of Peoria and State of Illinois, have invented certain new and useful Improvements in Adjustable Conveyer Supports for Conveyers, of which the following is a specification.

- 10 Our invention relates to an adjustable conveyer support for a conveyer.
The invention has special application to an adjustable thrust resisting member, interposed between a normal support or framing part of a thresher and the free end of a supporting bar, pivotally attached to a conveyer and to its relationing with respect to said support and bar, whereby said adjustable member is rendered active, through the movement of the conveyer, for effecting stop positioning of said conveyer.

The invention consists in the detailed fashioning of a rockable member, the relationing of the same to its support and to a supporting bar for a feeder, whereby longitudinal extension or retraction of the feeder bar will cause the rockable member to be shifted to different normal supporting positions against the thrust of said bar and to means for effecting inter-lock between the rockable member and the bar in non-normal positioning of the conveyer, whereby thrust action of the bar may cause the rockable member to be moved upon its support to a normal supporting position.

The invention also includes detailed structures essential to the relationing of the rockable member to its support and to the feeder supporting bar and to general combinations inclusive of the feeder and its connection with the thresher or feeder framing members.

Referring to the drawings:

Figure 1, is a side elevation showing a threshing machine and feeder parts and particularly showing the relationing of a conveyer thereto.

Figure 2, is a detailed view showing in side elevation parts serviceable for supporting a conveyer and indicating several positionings of said supporting parts.

Figure 3, shows in front elevation the same supporting parts that are shown in Figure 2.

Figure 4, is a detailed view of a rockable member and support. 55

The present invention is designed as an improvement on old methods for adjusting and supporting a conveyer in different positions. Heretofore the common and most improved method, in use, was and is, that of utilizing relatively extensible or retractable screw members positioned beneath the conveyer and requiring the application of a wrench to actuate the conveyer adjusting members. 60 65

In practice it has been found that two positions of the feeder are all that need be established to meet all the practical requirements in connection with the use of the conveyer as a receiving and carrying element 70 in unloading grain from vehicles or grain stacks.

It is our aim to simplify former conveyer supporting methods to the end of reducing cost and saving time. 75

The broad thought involved here has reference to the manual lifting of the conveyer to a normal high position and to the capability of utilizing gravity force under manual control to effect a lowering to a normal low position as distinguished from the screw acting methods hereinbefore mentioned. There is necessarily included, of course, in conjunction with the broad thought, certain means functioning in connection with the moving conveyer, which is herein shown to include a supporting bar, framing members, associated with the thresher body, and means actuated through the movement of the conveyer to establish 80 85 90 certain supporting and locked positions.

It will be seen that through our improvement the minimum of manual force is required, as such force is designed to be applied at the extreme outer end of the feeder 95 and furthermore, it is to the convenience of the operator or workman that such force may be so applied.

In the drawings, "A" and "B" refer to thresher and feeder parts. 10, is a conveyer 100 having a pivotal connection as at 11, with the framing parts of the feeder. 12, is a bar, the same being pivoted as at 13, to the body of the feeder. 14, is a flanged framing support. 15, is a plate applied to the flanged 105 portion of framing member 14, the same be-

ing fashioned at its lower portion with flanged seat 16, for the entry and seating of a cross framing tubular member 17, the latter being held in its position in said seat by means of rod 18, said rod also acting in conjunction with nut 19, and said tubular member to secure the lower end of plate 15 to the framing member. The upper end of plate 15 secured to the framing member by means 10 of short bolt 20 and nut 21. Plate 15 is also fashioned with a seat 22. 23 refers to a longitudinally bored body portion of a rockable member and 24—25 respectively to laterally projecting wing members attached 15 thereto. 26 is a seating boss member fashioned upon the body member 23 and wing member 24 and is adapted to be supported in seat 22 of plate member 15. Referring particularly to the wing members of the 20 rockable member (see Figure 2) 27 are rearward extensions from the main wing portions 24—25 and are slotted as at 28 to facilitate a seating support for the rear end of supporting bar 12. The rear end of bar 12 25 is transversely perforated and affords a seat for bolt 29, which bolt in practice is seated within slots 28 of the wing members.

Attention is called to Figure 2, wherein the operative result, with respect to differences in positioning of the rockable member, is shown, resulting from the raising or lowering of the feeder. In solid lines in this figure the feeder is being supported in its normal lower-most position, wherein 30 it appears that the rockable member has been thrust rearwardly, through the movement of bar 12, until bolt 29 is in contact with the extreme rear end of slot 28 and the bar is in contact with the main body portion 23 of the rockable member, thereby 35 effecting a complete stop against further lowering movement of the feeder. The broken line position of bar 12, shows a relative positioning of said bar and rockable member 40 when the conveyer is in its elevated supporting position, wherein it appears that bolt 29 rests in the extreme forward portion of slot 28 and in a position below a line through the centers of the bolt and the 45 support for the rockable member, whereby 50 thrust action of bar 12, will cause the contact portions 30, of wing members 24—25, to be lodged against the cross-frame sleeve member 17, thereby supporting the conveyer 55 in its normal elevated position.

In order that gravity force may be brought into play, in the lowering movement of the conveyer, to effect rearward rocking action of the rockable member, it 60 is necessary to first relieve said rockable member from its locked condition shown, in broken line position; therefore we have provided the pawl member 31, pivotally secured upon bolt 29, and the arcuately 65 fashioned laterally extending pawl seat 32,

on wing member 25, and attention is called to the relationing of said parts as shown in broken, as well as in dotted lines, in Figure 2, wherein it will be made to appear that upon raising the conveyer above its 70 normal elevated position, as shown in broken lines, to its position as shown in dotted lines, the resultant rearward projection of bar 12, will cause bolt 29, to be drawn forwardly upon the incline of the wall of slot 75 28 to approximately the maximum forward extremity of said slot, thereby carrying pawl 31 into the seating position, shown in dotted lines in said figure, in connection with arcuate pawl seat 32, and disposing bolt 29, in an off-center relation, with respect to the centering of the rockable member, and the bolt, thereby permitting thrust action of bar 12 to move the rockable member rearwardly, such thrust action of bar being possible because of the inter-lock effected between the pawl member and the pawl seat. In the rearward movement of the rockable member, resulting from the thrust of bar 12, at the lowering of the 90 feeder, it will be noted that bolt 29 is finally lodged at the extreme end of slot 28, whereas, in the locked position, of the pawl and pawl seat, it will be seen that said bolt is positioned some distance from the rear 95 end of said slot. This clearance space or extra length of slot is provided so that the pawl may be raised high enough to pass over the upturnel edge of the arcuate pawl seat 32, in order to be lodged in said seat and then again, this clearance space is necessary to provide for release of the pawl from its seat when the conveyer has reached its normal low supporting position, that it may 100 be free and inactive when the rockable member is again shifted in raising the conveyer to its normal elevated position.

The foregoing description, it is thought, has so clearly defined the operation of the device here in question that it is not thought necessary to further define the detailed operation of the device.

The invention herein is broadly directed to means associated with a pivoted conveyer and a supporting rod, actuated by the raising and lowering of the conveyer for positioning such means to effect stop and release action, to the end of effecting plural positioning of said elevator by the simple application of manual force, applied preferably, at the extreme outer end of said conveyer. We have here shown the means to accomplish the end above noted, but we do not confine ourselves to the specific means herein shown, but claim all means to the 110 same end that fall legitimately within the principle herein exemplified.

What we claim is:

1. In an adjustable conveyer, in combination, a supporting frame, a conveyer piv- 115 120 125 130

oted thereto, a reach member pivoted to the conveyer, a stop member connected with the framing, a rockable member pivoted respectively to the reach member and to the framing at a point below the pivotal connection of the conveyer thereto provided with a slot therein to facilitate adjustment of the pivotal member on the reach into off-centered relation above or below the pivotal center.

10 relation above or below the pivotal center of the adjustable member with the framing, whereby under conditions of raising the conveyer to a maximum working position the rockable member will be shifted into position for abutment with the stop and the

15 pivotable member on the reach would be disposed in the slot of the rockable member in a position below the center of the pivotal support of the rockable member, and whereby in disposing the convexon in its long

20 whereby in disposing the conveyer in its lowest working position action of raising the conveyer above its normal elevated working position will dispose the pivot member of the reach within the slot of the rockable

25 member in a position above the center of the support of the latter, whereby the weight of the conveyer will cause the rockable member to be shifted rearwardly and the pivot member thereon advanced to the rear.

30 pivot member thereon advanced to the rearward extremity of the slot therein to effect a stop and support for the conveyer in such maximum lowered position, and means associated respectively with the pivot member of the rearwardly located

of the reach and the rockable member for effecting interlock therebetween when the pivot member is disposed in the rearward portion of the slot thru the raising action of the conveyer above its normal high position.

of the conveyer above its normal high position whereby temporary interlock will be effected between the reach and rockable member to facilitate thrust action in the lowering movement of the conveyer will move the rockable member

move the rockable member rearwardly to permit rearward projection of the reach member into supporting relationship with the rockable member.

the rockable member.

2. In an adjustable conveyer, in combination, a supporting frame, a conveyer pivoted thereto, a reach member pivoted to the conveyer, a stop member connected with the framing, a rockable member pivoted respectively to the reach member and to the framing at a point below the pivotal connection of the conveyer thereto, a rigid

connection of the conveyer thereto provided with a slot therein to facilitate adjustment of the pivotal member on the reach into off-centered relation above or below the pivotal center of the adjustable member with the framing, whereby under conditions of raising the conveyer to a maximum working

60 ing the conveyer to a maximum working position the rockable member will be shifted into position for abutment with the stop and the pivotable member on the reach would be disposed in the slot of the rockable

55 and be disposed in the slot of the rockable member in a position below the center of the pivotal support of the rockable mem-

ber, and whereby in disposing the conveyer in its lowermost working position, action of raising the conveyer above its normal elevated working position will dispose the pivot member of the reach within the slot 70 of the rockable member in a position above the center of the support of the latter, whereby the weight of the conveyer will cause the rockable member to be shifted rearwardly and the pivot member thereon advanced to the rearward extremity of the slot therein to effect a stop and support for the conveyer in such maximum lowered position. 75

3. In a support for a pivoted conveyer, in combination, a framing member, supporting members connected respectively with the conveyer and the frame and associated for relative longitudinal reciprocation within defined limitation of interlocked extension or retraction of the length of the support, to provide variable workable positioning of the conveyer, and means operable from a raising movement of the conveyer to relieve the extended interlocked relation of the supporting members to permit the conveyer to be lowered.

4. In a device of the class described, in combination, a framing support, a conveyer pivoted thereto, a supporting member, comprising a reach and a stop member connected respectively with the framing and the conveyer and associated for relative longitudinal reciprocation to desired interlocked stop positions, to facilitate extension or retraction of the support to variably position the conveyer and means operable from a raising movement of the conveyer to relieve the extended interlocked relation of the supporting members to permit the conveyer to be lowered. 95 100 105

5. In a device of the class described, in combination, a framing support associated with a threshing machine, a conveyer pivoted thereto, reach members pivoted to the conveyer, adjustable members connecting the reach members to the framing support at a point below the connection of the conveyer therewith, stop members on the frame for maintaining the adjustable members in one of the desired working positions of the conveyer, and interlocking means associated respectively with the reach members and adjustable members normally disengaged but rendered temporarily interengageable through limited raising movement of the conveyer, whereby lowering movement of the conveyer will cause the adjustable member to be shifted rearwardly that the conveyer may be lowered to the limit permitted by the interlocked relation of the adjustable member and the reach. 125

6. In a device of the class described, in combination, a support, a conveyer pivoted thereto, a reach member pivoted to the conveyer, a rockable member pivoted to the 130

1 frame, provided with a slot therein and with a locking seat, a stop member on the frame adapted, under certain conditions of adjustment of the rockable member to maintain 5 the same in position that the slot therein will cross the vertical center of the pivotal connection of the rockable member with the frame, a pin at one end of the reach member connected with the slot in the rockable 10 member, whereby the reach member in a certain elevated position of the conveyer through thrust action and contact of the rockable member with the stop member will properly maintain the conveyer in one of its 15 working positions, a dog pivotally related to the pin on the reach member, temporarily engageable with the locking seat on the rockable member under conditions of limited raising movement of the conveyer, whereby, 20 through thrust action of the reach member in lowering the conveyer, the rockable member will be moved to a rearwardly disposed sustaining position for the conveyer in its maximum lowered working position.

25 7. In a device of the class described, in combination, a frame support, a conveyer pivoted thereto, adapted to be supported in certain definite raised and lowered working positions, an adjustable member pivoted to the frame, a stop on the frame adapted for 30 abutment with the adjustable member to maintain the conveyer in its maximum elevated working position, a reach, one end thereof pivoted to the conveyer and its opposite end adapted for connection with the 35 adjustable member, a pin on the reach member shiftably connected with the adjustable member to facilitate off-centered positioning of said pin with respect to the pivotal connection of the adjustable 40 member, with the support, whereby, in one position, thrust action of the reach will maintain the adjustable member in abutment with the stop, and in another position of the pin with respect to the adjustable 45 member, resulting from a limited raising of the conveyer and then a lowering movement thereof, the rockable member may be shifted rearwardly, and the reach in such movement will effect a shifting of the pin member 50 thereof to a stop position, whereby the conveyer will be maintained in its low working position.

In testimony whereof we affix our signature.

ARTHUR J. HARTLEY.
WILLIAM HALE.
